RECIPROCATING DOCTOR FOR PAPER-
MAKING AND ALLIED MACHINES

Arthur E. Broughton, Glens Falls, N. Y.

Application May 24, 1939, Serial No. 275,394

1 Claim. (Cl. 92—74)

This invention relates to doctors for the rollers and cylinders of paper making machines and allied machines.

To clean and clear the rollers and cylinders of such machines as paper making machines, it is highly desirable to employ reciprocating doctors. Many of the rollers and cylinders of these machines are of considerable length and in order to properly mount these reciprocating doctors, supports of sufficient strength and rigidity must be employed to assure correct and uniform pressure of the doctor blades over the full width of the rolls without permitting the doctor blades to sag, twist or vibrate.

It is the common practice at present to employ heavy supporting structures for the doctor blades and to reciprocate these heavy supporting structures with the blades. This necessitates the use of a great deal of power.

It is the main object of the present invention to provide a novel and improved doctor for rolls which includes a heavy supporting structure which extends across the width of the roll and is stationary and a light weight blade carrier and a light weight doctor blade carried thereby, the blade carrier being mounted and guided in the supporting structure for reciprocation therein by an expenditure of but a small amount of power and the supporting structure acting to properly hold the blade carrier and blade to assure uniform pressure of the blade over the full width of the roll.

Another object is to provide a structure such as above specified together with means permitting movement of the blade holder in the supporting structure with a minimum of friction while preventing twisting or turning of the blade holder relative to the supporting structure.

The objects and advantages of the invention will more fully appear from the following description, made in connection with the accompanying drawings, in which like reference characters refer to the same or similar parts throughout the various views and in which,

Fig. 1 is a plan view of a doctor embodying the invention looking down on the doctor from a plane taken parallel to the top surface of the supporting head;

Fig. 2 is a view taken chiefly in front elevation of the doctor, some parts being broken away and shown in section;

Fig. 3 is a vertical section taken on the line 3—3 of Fig. 2, as indicated by the arrows;

Fig. 4 is a vertical section taken on the line 4—4 of Fig. 2, as indicated by the arrows;

Fig. 5 is a vertical section taken on the line 5—5 of Fig. 2, as indicated by the arrows;

Fig. 6 is a view in vertical section of one of the ball bearing rollers employed; and

Fig. 7 is a plan view of a connecting yoke employed.

In Fig. 3 there is indicated a portion of a roller A of the type employed on paper making machines and other analogous machines and over a portion of the surface of which a web of paper is adapted to travel. To clean and clear such a roller, it is desirable to employ a reciprocating doctor, the doctor of the present invention being devised for such purpose and analogous purposes. As used on a paper making machine a roll such as the roller A is as long as the width of the sheet being formed and is accordingly of considerable length to extend across between the two side frames (not illustrated) of the machine.

In accordance with the present invention there is provided a heavy shaft 8 of such a length as to extend across between the two side frames adjacent the roller A and this shaft may be conveniently journaled in bearings 9 attached to any suitable supporting structure such as supports B. Attached to the shaft 8 is a heavy supporting bar 10 which may take the form of an angle bar as illustrated. Secured to one of the flanges of this angle bar as by screws 11 is a heavy supporting head 12, this head preferably having a projecting flange 12a partially received within a rabbit formed in the flange of the bar 10 to which the head is attached. The head 12, of course, extends the full length of the roller A and includes a flange 12b, a flange 12c set at right angles to the flange 12b, a flange 12d set at right angles to the flange 12c and projecting in the same direction therefrom as does the flange 12b, and it also includes a short lip 12e projecting from the flange 12d at right angles thereto in the same direction as the flange 12c projects therefrom. The head 12, accordingly, forms a channel 13 or way which is open at the forepart of the head 12.

Received within the channel 13 for reciprocating sliding movement therein, is a doctor blade holder which may be designated as an entirety by the letter C. This holder is of light weight and need not be of great strength inasmuch as it is supported by the supporting head 12. The holder C includes a bar 14 which is received within the channel 13. It also includes a blade carrier 15 having a flat strip portion 15a which is received within the channel 13 and overlies the bar 14 and is secured to the said bar as by means of screws 16. The blade carrier 15 outwardly of the channel 13 has a portion 15b which inclines diagonally downwardly from the strip portion 15a, is equipped with a longitudinal rib 15c near its point of juncture with the strip portion 15a, is equipped with a second longitudinal rib 15d somewhat outwardly from the rib 15c, and is provided with a longitudinal groove 15e in its upper surface near its lower edge to

produce a third bearing rib 15f at its top outer portion. Where the inclined portion 15b joins the strip portion 15a, an overlying substantially channel shaped bearing flange 15g is produced by the carrier 15 and this bearing flange terminates in a downwardly directed bearing edge 15h. The carrier 15 in the illustrated embodiment is formed of light weight extruded metal, such as aluminum, and it carries a light weight thin doctor blade 17 made preferably of spring steel and it also carries a tensioning plate 18 also of thin spring steel. The upper edge of the doctor blade 17 is received within a groove in the inclined portion 15b of the carrier and it projects across the channel 15e and has bearing against the bearing rib 15f. The tensioning plate 18 bears near its upper edge against the rib 15c and it bears at its lower edge against the doctor blade 17 outwardly from the point where the doctor blade contacts the bearing rib 15f. This tensioning plate 18 is also received between the rib 15d and the bearing edge 15h of the channel shaped portion 15g of the carrier. It will thus be seen that the light doctor blade 17 is properly supported by the carrier 15 and tensioned by the tensioning plate 18.

The holder C is supported for reciprocating sliding movement within the channel 13 of the head 12 by means of a plurality of rollers 19, 20, and 21 respectively, these rollers in turn being journaled for rotation on pins 22, 23, and 24 respectively, carried by the bar 14. The rollers 19 are carried by the pins 22 which project outwardly from the forward edge of the bar 14 and these rollers work through recesses 15i in the strip portion 15a of the carrier 15 and bear against the under surface of the flange 12b of the head near the outer edge thereof. The manner in which the rollers 19 are mounted is best shown in Fig. 3.

As best shown in Fig. 5 the rollers 20 are received within recesses 25 conjointly formed in the bar 14 and the strip portion 15a of the carrier 15 and the pins which carry the rollers 20 extend into these recesses at the rear side of the bar 14. The rollers 20 bear downwardly against the flange 12b of the head adjacent the rear portion thereof. The rollers 21, as best shown in Fig. 4, are received within recesses 26 formed partially in the top surface of the bar 14 and partially in the strip portion 15a of the carrier and, of course, the pins 24 project into these recesses 26 and the rollers 21 bear inwardly against the flange 12c of the head adjacent the point where the flange 12 joins the flange 12b.

In Fig. 6 and in Fig. 3 the detailed construction of one of the rollers 19 is illustrated, it being understood that the rollers 20 and 21 are of similar construction to the roller 19. The roller 19 is in reality a ball bearing and it includes an inner race 19a which is swaged on to the pin 22 carrying the roller and an outer race 19b which forms the tire of the roller and balls 19c work between the two races 19a and 19b and are received within the channels thereof.

Secured to one end of the head 10 as by a bracket 27 is a small fluid pressure reciprocating motor 28 which reciprocates a piston rod 29 working through a packing gland 30 carried by the motor 28. The fluid pressure reciprocating motor illustrated is of similar construc-

tion to that shown in my United States application for patent Serial No. 159,305, filed August 16, 1937, entitled "Reciprocating mechanism for paper making machines." The left end of the strip portion 15a of the carrier 15, in the illustrated embodiment, projects beyond the left end of the bar 14 and has secured thereto by means of screws 31 a yoke 32 which is connected by a pin 33 to the end of the piston rod 29.

It will be understood that the motor 28 will impart the reciprocating movement to the piston rod 29 and, of course, this movement will be imparted from the rod 29 through the yoke 32 to the holder C. Accordingly the holder will move back and forth in the channel 13 of the head 12 with the doctor blade 17 bearing against the roller A to be cleaned and being held under tension against the roller by means of the tension plate 18. Of course, as the holder C reciprocates within the head 12, the rollers 19, 20 and 21 which ride against the various portions of the head 12 will permit the light weight holder C to be properly guided and moved at an expenditure of but little force. The heavy head 12 supports the holder and gives the structure rigidity to assure correct and uniform pressure of the doctor blade over the full width of the roller A. The rollers 19, 20 and 21 are preferably staggered lengthwise of the holder C and, of course, the forward rollers 19 will prevent counterclockwise movement of the holder C in an upward direction, the rollers 20 will prevent counterclockwise movement of the holder in a downward direction, and the rollers 21 take the inward strain imposed upon the holders. Of course, these rollers form anti-friction supports for the holder. While only three such rollers are shown in Figs. 1 and 2, it is, of course, obvious that the views are broken to indicate greater length and other groups of similarly positioned rollers are used depending upon the length of the mechanism in each installation.

It will be seen that the present device has decided advantages over other types of reciprocating doctors wherein the complete structures for maintaining the doctor blades against the rollers being cleaned are reciprocated.

It will, of course, be understood that various changes may be made in the form, details, arrangement and proportions of the various parts without departing from the scope of the present invention which generally stated consists in the matter shown and described and as set forth in the appended claim.

What is claimed is:

In a reciprocating doctor, an elongated, continuous, supporting head adapted to extend across a roller, said head having a longitudinal channel therein of rectangular shape in cross section and said channel being open at the front of the head, a light bar received within said channel, a doctor blade secured to said bar, said bar having a blade holding portion which projects through the opening in the forepart of said head, a doctor blade tensioner carried by said blade holding portion, anti-friction rollers carried by said bar and working within said channel and supporting said bar for reciprocation therein, and means connected to said bar for reciprocating said bar together with said blade and tensioner relative to said head.

ARTHUR E. BROUGHTON.
